UNITED STATES PATENT OFFICE.

ALLEN JOHN GARVER, OF CLARKSTON, WASHINGTON.

APPARATUS FOR TREATING CINNABAR ORE.

1,369,738.

Specification of Letters Patent. Patented Feb. 22, 1921.

Application filed December 26, 1919. Serial No. 347,427.

To all whom it may concern:

Be it known that I, ALLEN J. GARVER, a citizen of the United States, and a resident of Clarkston, in the county of Asotin and 5 State of Washington, have invented a new and Improved Apparatus for Treating Cinnabar Ore, of which the following is a full, clear, and exact description.

This invention relates to improvements 10 in apparatus for treating cinnabar ore, and more particularly to an improved construction of retort and condenser which coöperate in the recovery of mercury from the ore, and which, of course, may be utilized in connection with other metallurgical processes, 15 an object of the invention being to provide improvements of the character stated, which facilitate the recovery of the mercury or other material and which economically 20 forms the operation.

A further object is to provide improved means for heating the ore while in a finely divided state and while moving downwardly in a retort over baffles which are heated and 25 then conducting the gas and fumes to an improved condenser where the mercury is recovered and deposited in suitable settling tanks.

A further object is to provide an improved 30 construction of condenser which operates to subject the fumes to the action of water and permits the mercury to escape as it is deposited and secures to a maximum extent the efficiency of the water in the condensing 35 operation.

With these and other objects in view the invention consists in certain novel features of construction, and combinations and arrangements of parts, as will be more fully 40 hereinafter described and pointed out in the claims.

In the accompanying drawings—

Figure 1 is a view partly in section and partly in elevation and more or less diagrammatic illustrating my improved apparatus;

Fig. 2 is a fragmentary view in vertical section on the line 2—2 of Fig. 1;

Fig. 3 is a view in elevation of the condenser;

Fig. 4 is a view in section on the line 4—4 of Fig. 3; and

Fig. 5 is a view in section on the line 5—5 of Fig. 4.

A represents my improved retort, B my improved condenser receiving the gases and

fumes from the retort. C represents a settling tank and D a flue adapted to recover any particles of mercury which escape from the condenser and operating as an adjunct to the condenser.

Retort.

My improved retort A consists of a hollow vertical column which is preferably of brick 65 although it may, of course, be made of any suitable material, the side walls of the retort having grooves 1 therein which grooves may, of course, be formed in the brick of the wall and in these grooves a vertical series 70 of staggered inclined baffles 2 are located. These baffles are also preferably of brick, but of course, the invention is not limited to the particular material employed.

A screw conveyer 3 located at the upper 75 end of the retort is adapted to feed fine particles of ore into the upper end of the retort which particles move downward through the retort over the baffles by gravity and are discharged through an outlet 4 at the bottom of the retort. I have illustrated an ordinary gate 5 closing the outlet 4, but it is obvious that any form of outlet closure may be provided and if desired, a closure 85 in the form of a screw propeller, such as indicated at 3, may be utilized to prevent the entrance of air at the bottom of the retort.

The bottom 6 of the retort is preferably inclined to the outlet 4 and under this bottom 6 an air pipe 7 is located and discharges 90 through the bottom upwardly into the retort. The admission of air may be controlled by a suitable cock 8 and the pipe may be arranged in the bottom in any desired way to utilize the heat of the ore to heat the 95 pipe and the air passing therethrough so that the air entering the retort has the desired temperature.

The baffles 2 are heated by means of burners 9. These burners are located in the walls 100 of the retort and project through openings 10 and are provided with suitable gates 11 which are slidably mounted so as to allow the entrance of air for purposes of combustion to be regulated to suit conditions. As 105 these burners are preferably located under the baffles 2, they heat the baffles to the necessary degree so that the fine particles of ore are roasted as they pass downwardly through the retort, meeting the heated air ascending 110 in the retort and generating gases or fumes, as will be readily understood.

Condenser.

The condenser B is preferably of cylindrical form, horizontally positioned or at an 5 incline, as desired, and mounted to revolve or rotate. While, of course, the invention is not limited to any particular means for causing a rotary motion to be imparted to the condenser, I have illustrated a simple form 10 of construction, which consists of the provision of circular racks 12 around the condenser and these racks are driven by pinions 13 on a shaft 14.

The shaft 14 is mounted in suitable bearing blocks 15 and receives power from any 15 desired source to impart a rotary motion to the condenser.

The cylindrical wall of the condenser is composed of longitudinal staves 16 and 17 20 alternately arranged. All of these staves are located at an incline or angle to the longitudinal axis of the condenser and the staves 16 are appreciably thicker than the staves 17 so that they project inwardly beyond the 25 inner edges of the staves 17 and provide, in effect, a circular series of inwardly projecting blades or veins with grooves between them. The staves 17 may be wider than the staves 16, as shown in Fig. 5, or any number of staves 17 may be located between the staves 16 to bring about the desired internal construction. The purpose of the inwardly 30 projecting blades or veins formed by the staves 16 is to exert an action on the water in the condenser to move the water around inside the condenser and also to throw the same rearwardly toward the outlet 21.

The condenser is provided at its ends with 40 heads 19 and 20 respectively and the inlet 18, above referred to, is in the head 19 and is of general truncated conical form as shown. The head 20 is provided with a central outlet 21 for the excess of air and with a circular series of outlets 22 communicating with the 45 spaces between the staves 16 so as to allow the mercury to move outwardly from the condenser into a conical spout 23. The spout 23 discharges the mercury and the water over a trough 24 into the settling tank C and it is to be understood that I will provide 50 a number of these settling tanks C so that when one is filled, it can be replaced by an empty tank and the filled tank set aside to allow the mercury to settle therein. The 55 outlet spout 23 is partially inclosed by the lower end of the vertical flue D, up which the gas and fumes, which escape from the condenser, are adapted to move.

This flue D is provided with a vertical 60 series of staggered baffles 25 and these baffles are preferably of some material that will absorb water so that they will operate to recover any particles of mercury that may be contained therein.

65 A suitable pump 26 and pipe 27 supply

water to the top of the flue D and this water passes downwardly over the baffles to keep them wet and counteract the tendency of the mercury and the gas to escape. The gas from the retort is conveyed to the condenser 70 B by means of a pipe 28 having inlets 29 communicating with the upper portion of the retort and provided between its ends with a fan or blower 30. A valve 31^a in said pipe is adapted to be moved to control the 75 draft therethrough and a water inlet pipe 31 projects into the pipe 28 near its outlet end and discharges in the direction of the flow of the gas and passes with the gas into the condenser B. The inlet 18 of the condenser B is of conical shape so that the outlet end of the pipe 28 can be inclined downwardly to discharge the gas and water into the bottom of the condenser and the pipe 80 can be thus positioned regardless of the rotary motion of the condenser. 85

The operation is as follows: The gas and fumes ascending in the retort are drawn through the pipe 28 and discharged into the condenser B mixed with water, as above explained, and in the condenser B the water is thrown upwardly and rearwardly by means of the staves 16 which form blades or veins. The mercury passes out through the outlets 22 and the water through the outlet 21 into 90 the spout 23 and from the latter flow into the acetylene tank C. Such mercury as is recovered in the flue also descends into the tank C and the latter, after it is filled, is removed and the mercury allowed to settle 95 so that it may be conveniently recovered.

While I have referred to my improved apparatus as one especially adapted for treating cinnabar ore to recover the mercury 100 therein, it is apparent that the apparatus might be used for other metallurgical processes and hence, I do not wish to be limited to any particular process, but desire to cover the apparatus broadly for any use to which it may be put. 110

Various slight changes may be made in the general form and arrangement of parts described without departing from the invention, and hence I do not limit myself to the precise details set forth but consider myself 115 at liberty to make such changes and alterations as fairly fall within the spirit and scope of the appended claims.

I claim:

1. An apparatus of the character stated, 120 comprising a rotary condenser, means for directing gas and fumes from a retort into the condenser, and a water discharge pipe communicating with said last-mentioned means.

2. An apparatus of the character stated, 125 comprising a substantially horizontal rotary condenser, means for directing gas from a retort into one end of the condenser, said condenser having outlets at its other end, 130

and a circular series of blades or veins in the condenser.

3. An apparatus of the character stated, comprising a substantially horizontal rotary condenser, means for directing gas from a retort into one end of the condenser, said condenser having outlets at its other end, and a circular series of blades or veins in the condenser, said blades or veins located at an angle to the longitudinal axis of the condenser.

4. An apparatus of the character stated, comprising a substantially horizontal rotary condenser having an inlet at one end and an outlet at its other end, means for directing gas and water from a retort into the inlet end of the condenser, a conical outlet spout positioned around the outlet of the

condenser, and said condenser having a circular series of ports connecting the inner 20 wall thereof with the said spout.

5. An apparatus of the character stated, comprising a substantially horizontal condenser having an inlet at one end and an outlet at its other end, a circular series of 25 internally projecting blades or veins in the condenser, said blades or veins located at an angle to the longitudinal axis of the condenser, a conical spout around the outside of the outlet of said condenser, said condenser having a circular series of outlets connecting the spaces between the blades or veins with said spout, and means for directing water into the inlet end of the condenser.

ALLEN JOHN GARVER.
